United States Patent

Des. 239,858
Patented May 11, 1976

239,858

LIGHTING FIXTURE

Tobia Scarpa, Via Campagna 3, Trevignano,
Treviso, Italy

Filed Nov. 25, 1974, Ser. No. 526,834

Claims priority, application Italy Sept. 30, 1974

Term of patent 14 years

Int. Cl. D26—03, 05

U.S. Cl. D48—4 B

FIG. 1 is a perspective view of a lighting fixture embodying my new design;

FIG. 2 is a side elevational view thereof on a reduced scale, the opposite side being identical thereto; and

FIG. 3 is a top plan view thereof on a reduced scale.

I claim:

The ornamental design for a lighting fixture, as shown and described.
